COMB

Joseph Vallis, Toronto, Ontario, Canada, assignor to Valden Company, Toronto, Ontario, Canada

Filed July 29, 1963, Ser. No. 76,022

Term of patent 14 years

(Cl. D86—8)

FIG. 1 is a side view of a comb showing my new design;
and

FIG. 2 is an enlarged fragmentary perspective view of a portion of the comb teeth shown in solid lines in

The dominant features of my design reside in the full line portions on the drawing and consist in short wide split teeth terminating in ball-like tips having longer more slender pointed teeth alternating between same, all as shown.

I claim:

The ornamental design for a comb, as shown and described.
